UNITED STATES PATENT OFFICE

EDWIN S. BISSONETTE, OF CLEVELAND, OHIO; THE GUARDIAN TRUST COMPANY AND PEARL M. BISSONETTE, EXECUTORS OF SAID EDWIN S. BISSONETTE, DECEASED, ASSIGNORS TO THE GUARDIAN EQUIPMENT COMPANY, OF CLEVELAND, OHIO, A CORPORATION OF OHIO

FIRE CONTROL MECHANISM

Application filed July 28, 1928. Serial No. 295,910.

My invention is an improvement in means for automatically operating at predetermined temperatures, various devices and mechanisms such as fire extinguishing systems, fire doors, booster pumps, alarms and the like.

One of the objects of this invention consists in automatically actuating at a predetermined degree of temperature, a device such as a control valve in a fire extinguishing system.

Another object of my invention is to accurately predetermine the temperature at which the mechanism will operate.

Another object of the invention resides in operating a device remotely situated from the area in which the temperature change takes place, substantially simultaneously with the predetermined degree of temperature change.

Other objects and advantages of my invention will become more apparent from the following description and the drawings forming a part of this specification, and in which like numerals are employed to designate like parts throughout the same.

Fig. 1 is a diagrammatic view of the preferred embodiment of my invention showing some of the parts in section;

Fig. 2 is a plan view of one form of a heat accumulator used in connection with my invention;

Fig. 3 is an elevation of another form of heat accumulator used in connection with my invention; and

Fig. 4 is an enlarged vertical section of a portion of the indicator tube and overflow receptacle showing the return orifice in the tube.

In the drawings, and particularly Figs. 1 and 2, I have illustrated the preferred form of my invention. The conduits 1 and 2 are preferably formed of copper tubing and may be enclosed within protective conduits, such as electric conductor conduits. These conduits 1 and 2 communicate with each other through a coupling 3, one end of the conduit 1 being connected to a device such as a heat accumulator A, and the other end is connected through a coupling 4 and pipe 5 to a liquid supply reservoir 5'. The other end

of the conduit 2 communicates through a coupling to the interior of an expansion bellows 19. A liquid supply control valve of the float type is indicated at 7 and is interposed between the supply reservoir 5' and the conduit 5. It will be seen that when the level of the liquid in the conduit 5 recedes the ball will be unseated from the seat 8 formed in the casing 6 and will permit liquid to flow into the casing and conduit from the reservoir until the level raises the float to its seat 8 to shut off the supply. The operation is thus automatic and insures a capacity of liquid within the system at all times. The liquid which I prefer to use in connection with my invention is carbon tetrachloride (CCl_4), since this is quickly responsive to temperature changes and expands readily, although I have found other substances such as alcohol or a mixture of glycerine and alcohol to be suitable for use in connection with my invention.

I have provided a pressure indicating means which includes a closed chamber 10 connected through a pipe 11 to the conduit 5, and a tube 12 extending into the chamber and communicating at its upper end with the interior of an overflow receptacle 13. I also provide a scale conveniently graduated to indicate pressure exerted on the liquid in the system, and which is located immediately behind the tube 12 for reading the level of a liquid, such as mercury, within the receptacle 10 and indicated at Hg . The tube 12 is provided with an orifice 14 located at a point in the tube near the bottom of the receptacle 13 to permit any overflow within the receptacle to flow back through the tube when the mercury level in the tube is below the orifice. I have thus provided means not only for indicating the pressures within the conduits 1, 2 and 5, but have also provided means for conserving any of the mercury overflow that may be caused by abnormal pressures within these conduits.

I have also provided means for transmitting changes in temperature of an area in which the means is placed, which, according to the preferred embodiment of my invention shown in Figs. 1 and 2 consists of a hollow

disc-like structure having communication with the conduit 1 through a coupling 15. This means is in the nature of a heat accumulator and is preferably constructed of sheet copper or other material which is a good conductor of heat. The upper and lower sections 16 and 17, respectively, are corrugated, as shown, to provide greater heat accumulating surfaces, and the space between these sections is filled with the liquid supplied through the conduit 1. The accumulator is provided with suitable couplings 15 and 18, the latter being plugged when the apparatus is used as illustrated.

15 One end of the conduit 2 is coupled to an expansion bellows 19, permitting the liquid to enter the same and exert its pressure to expand the bellows toward the right. Thus it will be seen that when the liquid expands 20 as the result of a rise in temperature in the vicinity of the device A the pressure created will be transmitted by the liquid to expand the bellows toward the head 26 of the arm 20.

I have also provided means operable by the 25 expansion of the bellows for actuating a given object such as a control valve in a fire extinguishing system, a booster pump, fire doors, alarms and the like. This means may be mounted on a panel C and includes a cam 30 21 rotatable on a shaft 22. To facilitate the movement of the cam I provide roller bearings between the cam and its shaft. The cam is cut away as at 23 for purposes which will be described presently. A link 24 is connected 35 at one end to the cam as at 25 and its other end carries an adjustable arm 20 having an enlarged head on one end and engageable with an end of the expansion bellows. The opposite end of the arm 20 is screw threaded 40 into an opening in the link 24 and may be adjusted axially with respect to the link by means of a lock nut 27. In this manner the head 26 may be set a predetermined distance from the adjacent end of the bellows so that 45 the latter will operate the link and cam only when the fluid expands the bellows sufficiently to engage the head 26, and corresponding to a predetermined temperature in the vicinity of the heat accumulator. The arm 20 may be 50 graduated if desired so that the operator may adjust the arm to be engaged by the end of the bellows at a predetermined point of its expansion.

A counter weight 28 is pivotally attached 55 to the cam and normally tends to rotate the cam in a counter clockwise direction to bring the head 26 into contact with the adjacent end of the bellows.

In the embodiment illustrated I have shown 60 a control valve D as the device to be operated by a predetermined rise in temperature, but it will be understood that other devices and mechanisms such as fire doors, booster pumps, alarms, and so forth, may be similarly operated. As shown in the drawings the valve D

is provided with a handle or lever 31 having a perforated end as at 32.

A weight 33 is normally suspended from one end of a rocker arm 34 by means of a headed wire or rod 35. The head or stop 36 normally is seated in the bifurcated end 37 of the arm 34. The arm 34 is pivoted to rock about the fulcrum 38 and its other end is provided with an upwardly projecting trip 39. A pair of links 40 and 41 are pivotally connected at their adjacent ends as at 42 and carry an idle roller 43 which normally engage the periphery 44 of the cam, and which when the cam is rotated will roll along the walls of the cut away portion 23 of the cam, 80 thus lifting the trip end 45 of the link 41 from the trip 39 and allowing the weight 33 to rock the arm 34 about its pivot in a clockwise direction, whereupon the head 36 is unseated and the weight 33 is released. The drop of 85 the weight is sufficient when thus released to rock the lever 31 and operate the device D.

In Fig. 3 I have illustrated a second form 90 of heat accumulator B which consists preferably of a sheet copper sphere having a coupling 51 for connection with the conduit 1.

Various changes may be made in the details 95 of construction of my invention without departing from the spirit of the invention or the scope of the subjoined claims.

I claim:

1. A heat control device comprising a closed fluid system including a heat accumulator and an expansion member, counterweighted mechanism normally held inoperative, and means actuated by the expansion member upon application of heat to the heat accumulator for releasing the counterweight whereby the mechanism is actuated. 100

2. A heat control device comprising a closed fluid system including a heat accumulator and an expansion member counterweighted operative mechanism normally held inoperative, and means including a cam operated by the expansion member upon the application of heat to the accumulator for releasing the counterweight whereby the operative mechanism is actuated. 110

3. A heat control device comprising a closed fluid system including a heat accumulator and an expansion member, operative mechanism, cam means adapted to be actuated by the expansion member upon the application of heat to the accumulator, a roller carried by links associated with the cam means, said links normally holding said operative mechanism inoperative, said roller bearing against the cam means and adapted to be operated thereby to actuate the operative mechanism. 115

4. A heat control device comprising a closed fluid system including a heat accumulator and an expansion member, the latter adapted to be actuated by the fluid of the system upon the application of heat to the ac- 130

cumulator, fluid supply means, and means for permitting passage of fluid from the fluid supply means to the fluid system while preventing reverse flow thereof.

5 In testimony whereof he hereunto affixes his signature this 24th day of July, 1928.

EDWIN S. BISSONETTE.
